UNITED STATES PATENT OFFICE.

MOSES S. DEARBORN, OF OAKLAND, CALIFORNIA.

ADJUSTABLE MITER BOX.

Application filed January 21, 1925. Serial No. 3,883.

To all whom it may concern:

Be it known that I, MOSES S. DEARBORN, a citizen of the United States, residing at Oakland, in the county of Alameda and 5 State of California, have invented certain new and useful Improvements in Adjustable Miter Boxes, of which the following is a specification.

This invention relates to certain improvements in miter boxes, and has for its object 10 to provide a box of such class, in a manner as hereinafter set forth, with means to enable a saw to be held in a vertically inclined plane while cutting diagonally across 15 an object, so as to cut angles in two directions at the same time and further whereby the saw will be effectively maintained in its various adjustments and further whereby the saw adjustments can be conveniently obtained when occasion requires. 20

Further objects of the invention are to provide, in a manner as hereinafter set forth, a miter box which is comparatively simple in its construction and arrangement, 25 strong, durable, compact, thoroughly efficient and convenient in its use, readily assembled and comparatively inexpensive to set up.

With the foregoing and other objects in 30 view, the invention consists of the novel construction, combination and arrangement of parts, as hereinafter more specifically described and illustrated in the accompanying drawings, wherein is shown an embodiment 35 of the invention, but it is to be understood that changes, variations and modifications can be resorted to which fall within the scope of the claims hereunto appended.

In the drawings wherein like reference 40 characters denote corresponding parts throughout the several views:—

Figure 1 is a top plan view of a miter box in accordance with this invention.

Figure 2 is an inverted plan view thereof.

Figure 3 is a section on line 3—3, Figure 45 1.

Figure 4 is a section on line 4—4, Figure 1.

Figure 5 is a section on line 5—5, Figure 50 1.

Figure 6 is a section on line 6—6, Figure 1.

Referring to the drawings in detail, a miter box in accordance with this invention 55 includes a table consisting of a top formed

of a pair of spaced lengthwise aligning outer sections 1, 2 of substantial length and each having its inner end inclined as at 3.

The inclined inner ends of the sections 1, 2 extend in opposite directions with respect 60 to each other and the inclination of each of said ends is outward in a direction towards the outer side edge of the section. The sections 1, 2 are spaced from each other at the inner corners thereof. The table top 65 further includes an intermediate section, referred to generally by the reference character 4, and which is arranged below and extends forwardly and rearwardly from the sections 1, 2. The section 4 comprises a 70 rectangular body portion 5, a forward segment extension 6 and a rear semi-circular extension 7. The extension 6 terminates in the end edges of the body portion 5 and further projects forwardly from the outer 75 side edges of the sections 1, 2. The body portion 5 is of a length to extend from a point between the inner end and outer end of the section 1 to a point between the inner end and outer end of the section 2. The 80 body portion 5 of the section 4 is secured to the sections 1 and 2 by holdfast devices 8 arranged in proximity to the inner end 3 of the sections 1 and 2. The semi-circular projection 7 is positioned centrally of the 85 rear edge 9 of the body portion 5 of the section 4 and is materially smaller than extension 6.

The section 1, as well as the section 2 at 90 its rear thereof, is formed with a vertically disposed flange 10, provided near its bottom with a lengthwise extending rectangular slot 11, and further having its inner end, vertically disposed for a portion of its height as at 12 and the remaining portion 95 upwardly and outwardly inclined as at 13. The inclined portion of the inner end of the flange of the section 1 extends in an opposite direction with respect to the inclined portion of the flange of the section 2. The 100 vertical portions 12, at the inner ends of said flange extension, are spaced from each other.

The table further includes a pair of inverted yoke-shaped supports each consisting 105 of a head-piece 14, a pair of legs 15 depending from the head-piece 14 and each of which is laterally flanged at its lower end, as at 16. The head-pieces 14 are of a length greater than the width of the sections 1 and 110

2 and projects rearwardly therefrom. The sections 1 and 2 are secured to the head-pieces 14 by the holdfast devices 17. The flanges 16 are apertured as at 18 for the passage of holdfast devices to fixedly secure the table top in position.

Extending from the inner end 3 of the section 1 to the inner end 3 of the section 2, as well as being secured to and positioned 10 on the upper face of the section 4, is a segment-shaped bar 19 provided with a graduated scale 20. The bar 19 also projects on the extension 6, and associating with the scale 20 is a pointer 21.

15 Pivotedly supported from the table and extending forwardly and rearwardly therefrom is an angle adjusting mechanism for a tiltable saw carrier. The said angle adjusting mechanism comprises a flat rectangular plate 22 and a flat rectangular plate 23 positioned against the lower face of the plate 22 and which is of less length than the length of the latter. The plate 23 projects rearwardly from the plate 22 and is formed 20 with a vertically disposed flange 24. The forward end of the plate 23 terminates at a point removed from the forward end of the plate 22 and is fixedly secured to the latter by holdfast devices 25.

30 Extending downwardly from the section 4, of the table top centrally of the rear of said section 4 is a pivot bolt 26 which projects through the plates 22 and 23 and carries on its lower end a securing nut 27. The plates 22 and 23 shift bodily on the bolt 26. A washer element 28 is mounted upon the plate 22 and through which element the bolt 26 projects. A spacing member 29 is secured to the upper face of the plate 22 35 near the forward end thereof and which is arranged beneath the projection 6.

Secured to the lower face of the plate 22, at the forward end thereof, is an angle-shaped finger-piece 30 to facilitate the shifting of the plates 22 and 23 when occasion requires.

The plate 22 projects forwardly from the projection 6, of the section 4, and has secured to its upper face, forwardly of the projection 6, an angle-shaped member 31 which overlaps the upper face of the projection 6 and said member 31 has the pointer 21 formed integral therewith and offset with respect thereto. The pointer 21 overlaps the bar 19 so as to co-act with the scale 20 when shifting the plates 22 and 23 for the purpose of adjusting the saw carrier at an angle. Extending through the members 29 and 30, as well as the plate 22, and further threadably engaged therewith, is a set screw 32, which binds against the lower face of the projection 6, for the purpose of maintaining the plates 22 and 23 in position to which they have been adjusted with respect to the 65 scale.

The plates 22 and 23, rearwardly of the table top, are formed with lengthwise extending rectangular openings 33 which register with each other and the plate 22 at its rear end is formed with a transverse opening 34 registering with a transverse opening 35 formed in the plate 23 forwardly of the flange 24.

70 Mounted against the upper face of the plate 23, and against the forward face of the flange 24, is a quadrant-shaped member 36, having a centrally disposed depending portion 37 which projects through the opening 35. Holdfast devices 38 are employed for fixedly securing member 36 to the flange 24. The member 36 projects a substantial distance above the flange 24 and has secured to its forward face a flat segmental bar 39 provided with a graduated scale 40.

80 Arranged forwardly of the member 36, as well as projecting thereabove, is a vertically disposed lever arm 41, which extends through the opening 35. The lever arm 41 is pivotally mounted on a bolt 42, which extends through the lower portion of said arm, said member 36 and the flange 24. The bolt 42 projects rearwardly from the flange 24 and carries a washer 43 and a clamping nut 44. The rear face of the lever arm 41 is grooved as at 45 to provide a clearance for 85 the bar 39 when the lever is shifted in either direction. The rear face of the lever arm 41, has secured therewith, above the member 36, by the holdfast devices 46, an angle-shaped bracket 47, which overlaps the rear 90 of the member 36 and carries a set screw 48 adapted to bind against the member 36 for the purpose of maintaining the lever arm 41, in the position to which it has been adjusted. The upper end of the lever arm 41 is 95 provided with a lengthwise opening 49 for a purpose to be presently referred to.

100 The saw-carrier comprises a saw guide section and a coupling section and the former consists of a pair of side members 110 each formed of a flat top bar 49, a vertically disposed front bar 50 and a vertically disposed rear bar 51. The rear bar 51 of one of the side members is extended rearwardly 115 to provide upper and lower projections 52, 53 and with the former of greater length than the latter. The projection 52 is positioned at the top of such side member and the projection 53 at the bottom thereof. The top bars 49 of the side members are 120 arranged below the upper ends of the front and rear bars thereof. Arranged between the upper portions of the side members is a longitudinally extending spacing member 54, secured in position by holdfast devices 125 55 and having its lower edge positioned slightly below the upper edge of the top bars 49. Secured to the inner face of each front bar 50, as well as the inner face of each rear bar 51, is a vertically disposed saw pas- 130

sage forming member 56. The members 56 carried by the bars 50 are spaced of each other and the members 56 carried by the bars 51 are spaced of each other. Holdfast devices 57 are employed for fixedly securing a spacing member 54 to its respective bar of a side member of the saw guide. The bars 50 are arranged a substantial distance from the bars 51 so that the saw guide will overlap the work operated on, which is indicated at 58 in Figure 4.

Connected to one of the side members of the saw guide, through the medium of an attaching bracket 59, is a saw depth gauge 60.

The coupling section of the saw guide consists of an angle-shaped attaching member 61, having one of its arms, indicated at 62, fixedly secured by the holdfast devices 63 to the forward face of the lever arm 41. The other arm of the member 61, and which is indicated at 64, projects forwardly and has pivotally connected at its top, as at 65, a forwardly extended link 66. The arm 64, of the member 61, at its lower end, has pivotally connected therewith, as at 67, a forwardly extending link 68. The link 66 is pivotally connected to the projection 52 as at 69 and the link 68 is pivotally connected to the projection 53 as at 70 and said link 68 projects forwardly with respect to the link 66. The construction of the coupling section permits of the links 66 and 68 to be swung on the pivots 65 and 67 to a vertical position carrying the saw guide therewith whereby the latter can be held in an elevated position and suspended at right angles with respect to the links 66 and 67 when these latter are shifted to vertical position. The saw guide can swing on the pivots 69 and 70.

The connecting of the saw carrier to the lever arm 41 permits of the carrier to be adjusted at various vertical inclined planes, as when the lever arm 41 is adjusted with respect to the scale 40 the saw-carrier will be carried therewith. The adjustment of the saw-carrier by the angle adjusting mechanism therefor and the further adjusting of the saw-carrier by the lever arm 41 enables the saw to be held in a vertically inclined plane while cutting diagonally across an object, so as to cut angles in two directions at the same time.

An adjustable guide mechanism is employed in connection with the saw-carrier for the purpose of guiding the saw guide in the position to which it has been adjusted and also to permit of the saw carrier to tilt away from a vertical plane. The said guide mechanism comprises a pair of vertically disposed back rest extension slides, between which passes the saw carrier, and which are automatically shiftable towards and from the saw carrier to per-

mit it to tilt away from the vertical plane. The said slides are indicated at 71, 72, are mounted on the flanges 10 and shift lengthwise, and further the said slides are spring controlled and the controlling spring therefor will be presently referred to. The slides 71 and 72 are bent to overlap the upper portions of the flanges 10 and each of said slides has connected therewith a depending bracket 73 through the medium of a coupling element 74 which extends through the upper portion of the bracket 73, through a slot 11 and is secured to the lower portion of the slide. Each bracket 73 is arranged rearwardly of the flange 10 and has mounted therein a grooved roller 75. Each bracket 73 is furthermore provided with a forwardly extending angle-shaped arm 76, and the arm 76 of one bracket 73, is connected to the arm 76 of the other bracket 73 by a coiled pulling spring 77, which extends transversely of the lower face of the plate 23 and provides the controlling spring for the slides 71, 72.

Mounted between the section 4 of the table top and the washer element 28 is a semi-circular projection 78 which swings on the pivot bolt 26. Formed integral with and extending rearwardly from the projection 78, as well as positioned rearwardly with respect to the section 4, is a shiftable curved actuating plate 79 having its side edges bearing against the rollers 75, and said plate 79 provides means for moving one of the slides 71, 72 relatively to each other when the plate is shifted in a manner to be presently referred to. The lower face of the plate 79 is formed with a segment-shaped rack 80. Secured to the lower face of the plate 23, forwardly of the opening 33, is a bearing bracket 81 and secured to the lower face of the plate 23 in proximity to the rear end thereof is a bearing bracket 82. Journalized in the brackets 81 and 82 is a spring controlled shaft 83 capable of being shifted lengthwise with respect to the plate 23. The shaft 83 carries a gear or pinion 84 adapted to mesh with the rack 80 for the purpose of shifting the plate 79 whereby one of its side edges bearing against a roller 75 will cause the shifting of one slide relatively to the other against the action of the spring 77 and permit the saw carrier to tilt away from the vertical plane.

When it is desired to adjust the saw-carrier in a vertical inclined plane, the pinion 84 is shifted clear of the rack 80 and for such purpose the shaft 83, carries a handle member 85 on its rear end and said member 85 has an offset upper portion 85' carrying a pin 86 for connecting the member 85 to the lever arm 41. The opening 49' provides means for the passage of the pin 86 to couple the handle member 85

to the lever arm 41 thereby locking the shaft 83. The member 85 has its rear face formed with a series of cavities 86' to receive the pin 86 to maintain member 85 in a vertical position. The slots 33 in the plates 22 and 23 provide a clearance to enable the shifting of the pinion 84 clear of the rack 80. See dotted line position Figure 4. After the shaft 83 has been released it can be adjusted and locked by the shifting of the handle member 85 towards the lever 41, so that pin 86 will engage in the lever arm 41, but such shifting movement rocks the shaft 83 in the desired direction whereby the plate 79 will be shifted thereby moving one of the slides, and after the shaft 83 is locked the slide will support the saw-carrier in adjusted position and owing to the action of the controlling spring for the slides they will bind against the saw-carrier and support it.

Extending through the plates 22 and 23 is a shiftable locking device 87 which includes upper and lower plates 88, 89, respectively. The plates 22 and 23 are formed with aligning slots 90 in which the locking device can shift and said plates 88 and 89 are of greater width and greater length than the slots 90. The plate 88 overlaps the grooved actuating plate 79 and constitutes means for maintaining it in parallelism with respect to the plate 22. The locking device slides back and forth in the slots 90, but overlaps the actuating plate 79 under all conditions and further prevents the springing upwardly of the rear of the plate 79 relative to the plate 22. The plate 29 is arranged below the plate 23.

The controlling spring for the shaft 83 is indicated at 91 and is interposed between a guide 92 and a pinion 84 and when released the said spring 90 acts as a means to maintain the pinion 84 in mesh with the rack 80. When the shaft 83 is shifted rearwardly to unmesh the pinion 84 from the rack 80 such movement is had against the action of the spring 91 and when the pin 86 is in engagement with one of the cavities 86' the spring 91 acts to hold the handle member 85 in a vertical position. When the spring 91 is released it further acts to maintain the offset portion 85', of the handle member 85, in contact with the rear face of the lever arm 41. The guide 92 is secured to and depends from the plate 23 and when the shaft 83 is shifted rearwardly the pinion 84, in connection with the guide 92, compresses the spring 91 whereby the tension is applied thereto, so that when the handle member 85 is released the spring 91 will cause the pinion 84 to be shifted in mesh with the rack 80.

It is thought that the many advantages of the miter box in accordance with this invention can be readily understood, and although in the construction herein shown and

described, the invention is embodied in its preferred form, yet it is to be understood the changes in details of construction can be readily had without departing from the invention as claimed.

70

What I claim is:—

1. A miter box comprising a table, a saw carrier angle adjusting mechanism pivotally mounted thereon and including means for positioning the saw carrier at an angle with respect to the work and in a plane inclined to the vertical, a saw carrier connected to said mechanism and bodily shiftable therewith, and a pair of back rest extension slides between which passes the saw carrier, said slides automatically shiftable towards and from the carrier to permit it to tilt away from a vertical plane.

75

2. A miter box comprising a table, a saw carrier angle adjusting mechanism pivotally mounted thereon and including means for positioning the saw carrier at an angle with respect to the work and in a plane inclined to the vertical, a saw carrier connected to said mechanism and bodily shiftable therewith, a pair of back rest extension slides between which passes the saw carrier, said slides automatically shiftable towards and from the carrier to permit it to tilt away from a vertical plane, and means for adjusting one of said slides relatively to the other.

85

3. A miter box comprising a saw carrier, an angle adjusting mechanism therefor and including means for positioning said saw carrier at a plane inclined to the vertical, and a pair of back rest extension slides one shiftable relatively to the other to permit the carrier to tilt away from the vertical plane, said slides automatically shifted to 100 towards the carrier.

90

4. A miter box comprising a saw carrier, an angle adjusting mechanism therefor and including means for positioning said saw carried at a plane inclined to the vertical, 110 a pair of back rest extension slides one shiftable relatively to the other to permit the carrier to tilt away from the vertical plane, said slides automatically shifted toward the carrier, and means for shifting said slides 115 one relatively to the other away from the carrier.

95

5. A miter box comprising a saw carrier, an angle adjusting mechanism therefor and including means for positioning said saw carrier at a plane inclined to the vertical, a pair of back rest extension slides one shiftable relatively to the other to permit the carrier to tilt away from the vertical plane, said slides automatically shifted toward the carrier, means for shifting said slides one 120 relatively to the other away from the carrier, said saw carrier connected to said adjusting mechanism, a table on which said mechanism is pivotally mounted, and means 125

125

130

carried by the table and engaging with said mechanism for locking it in adjusted position.

6. A miter box comprising a saw carrier, an angle adjusting mechanism therefor and including means for positioning said saw carrier at a plane inclined to the vertical, a pair of back rest extension slides one shiftable relatively to the other to permit the carrier to tilt away from the vertical plane, said slides automatically shifted towards the carrier, means for shifting said slides one relatively to the other away from the carrier, said saw carrier connected to said adjusting mechanism, a table on which said mechanism is pivotally mounted, means carried by the table and engaging with said mechanism for locking it in adjusted position, and the said means for shifting one of said slides relatively to the other detachably engaging with said mechanism for maintaining the adjusted slide in adjusted position.

7. A miter box comprising a table, a saw carrier angle adjusting mechanism pivotally mounted thereon, a saw carrier, adjustable means carried by said mechanism and connected with the carrier for shifting it to a plane inclined to the vertical, a pair of shiftable back rest extension slides, one arranged at each side of the saw carrier and providing means to permit the latter to tilt away from a vertical plane, and means carried by said mechanism for shifting one of said slides relatively to the other.

8. A miter box comprising a table, a saw carrier angle adjusting mechanism pivotally mounted thereon, a saw carrier, adjustable means carried by said mechanism and connected with the carrier for shifting it to a plane inclined to the vertical, a pair of shiftable back rest extension slides, one arranged at each side of the saw carrier and providing means to permit the latter to tilt away from a vertical plane, and means carried by said mechanism for shifting one of said slides relatively to the other, said means for shifting the slides and said mechanism having coacting means to retain the adjusted slide in adjusted position.

9. A miter box comprising a saw carrier formed of a shiftable saw guide section and a shiftable coupling section, said saw guide section having its rear end pivotally connected to the forward end of the coupling section whereby when the coupling section is shifted said saw guide section can extend at right angles with respect thereto,

said saw guide section provided with a saw passage, an angle adjusting means for said saw carrier, said coupling section pivotally connected with said angle adjusting means whereby said coupling section can be swung upwardly with respect to said angle adjusting means carrying the saw guide section therewith and whereby the latter can be positioned at right angles with respect to the coupling section.

10. A miter box comprising a saw guide, a pivotal supporting mechanism therefor permitting positioning said guide diagonally with respect to the work and at a plane inclined to the vertical, and means for connecting the rear end of said guide to said mechanism, said means including a plurality of parallel pivoted links for permitting shifting said guide upwardly while maintaining it parallel.

11. A miter box comprising a saw guide, a pivotal support therefor and permitting positioning said guide diagonally with respect to the work, adjustable means carried by said support and connected with the saw guide for positioning the latter at a plane inclined to the vertical, said support and said means having coacting elements for locking said means in adjusted position, means for detachably locking said support from movement, and a spring controlled back rest mounted on the support and shiftable towards and from the carrier to permit the latter to tilt away from a vertical plane.

12. A miter box comprising a saw guide, a pivotal support therefor and permitting positioning said guide diagonally with respect to the work, adjustable means carried by said support and connected with the saw guide for positioning the latter at a plane inclined to the vertical, said support and said means having coacting elements for locking said means in adjusted position, means for detachably locking said support from movement, a spring controlled back rest mounted on the support and shiftable towards and from the carrier to permit the latter to tilt away from a vertical plane, and operating means for said back rest, said operating means and said means for adjusting a saw carrier at a plane inclined to the vertical having coacting elements for detachably locking said operating means from movement.

In testimony whereof, I affix my signature hereto.

MOSES S. DEARBORN.
